UNITED STATES PATENT OFFICE.

WILLIAM C. PEET, OF NEW YORK, N. Y., ASSIGNOR TO THE J. L. MOTT IRON WORKS, OF SAME PLACE.

DESIGN FOR A BATH-TUB.

SPECIFICATION forming part of Design No. 32,712, dated May 22, 1900.

Application filed April 21, 1900. Serial No. 13,811. Term of patent 7 years.

To all whom it may concern:

Be it known that I, WILLIAM C. PEET, a citizen of the United States, residing at the city of New York, in the county and State of New York, have invented and produced a new and original Design for a Bath-Tub, of which the following is a specification, reference being had to the accompanying drawings, forming part thereof, in which—

Figure 1 is a plan, and Fig. 2 an elevation, showing my new design. Fig. 3 is a longitudinal section upon the line xx of Fig. 1, and Fig. 4 a cross-section upon the line yy of Fig. 2.

The general configuration of the bath-tub is rectangular, and, as shown in the drawings, the leading or essential feature of my design consists in the swell surface between the molded base and the molded rim adjacent to the molded base.

The sides and ends of the bath-tub are straight, and a represents the molded rim with one rounded corner, and b a small rib beneath the molded rim a .

c represents the swell surface, which in the drawings is shown along one side and end of the bath-tub.

d represents the rib at the base of the bath-tub adjacent to the flat bottom and having a vertical face, e a small rib, and f a cove between the base-rib d and the swell surface c .

What I claim is—

The design for a bath-tub, substantially as shown and described.

Signed by me this 2d day of April, 1900.

WILLIAM C. PEET.
